MECHANICAL STOKER

Albert C. Schickler, Shaker Heights, Ohio, assignor to The Economy Electric Products Company, Cleveland, Ohio, a corporation of Ohio

Application October 7, 1931, Serial No. 567,399

6 Claims. (Cl. 110—109)

This invention relates generally to fuel feeding devices, and more particularly to an improved form of mechanical stoker.

An object of the present invention is to provide a mechanical stoker of simple and economical construction, and suitable for use with domestic furnaces and other forms of heating apparatus.

Another object of this invention is to provide a mechanical stoker of compact form, which is mounted upon, and movable with, a furnace door or like member, such that installation can be made on previously erected furnaces by simply attaching the door carrying the stoker, and such that access to the interior of the furnace can be had for any purpose, by moving the door to its open position.

Another object of this invention is to provide a mechanical stoker having novel power means for actuating the same.

A further object of this invention is to provide a mechanical stoker having a fuel-feeding plunger which is operated by means including a hydraulically actuated diaphragm.

Still another object of this invention is to provide mechanical stoking apparatus having novel control means, and embodying a fuel feed tube which is rotatable about its axis to facilitate the charging of the fuel hopper.

Other objects and advantages of this invention will be apparent from the following description, when taken in conjunction with the accompanying sheets of drawings, wherein

Figure 1 is a side elevational view of a mechanical stoker embodying my invention;

Fig. 2 is a front elevation thereof;

Fig. 3 is a plan view thereof with the hopper removed and showing a portion of the furnace in section;

Fig. 4 is a vertical sectional elevation taken on line 4—4 of Fig. 2;

Fig. 5 is a partial sectional plan view taken on line 5—5 of Fig. 2;

Fig. 6 is a sectional elevation taken on line 6—6 of Fig. 4;

Fig. 7 is a plan view showing a portion of the mount with the feed tube removed;

Fig. 8 is a sectional view taken on line 8—8 of Fig. 5;

Fig. 9 is a sectional view of one of the control valves; and

Fig. 10 is a sectional view of a thermostat forming a part of the automatic control means for the stoker.

In the drawings, to which detailed reference will presently be made, I have shown the pre-

ferred embodiment of my invention in the form of a mechanical stoker, which is of simple and compact construction, economical in operation, and especially suitable for use with domestic furnaces. Before proceeding with a detailed description of the device, it should be understood that my invention may be embodied in structural forms other than that herein illustrated, and that the utility of the device is by no means restricted to domestic heating apparatus.

In its preferred embodiment, as illustrated in the drawings, my mechanical stoker is of the over-feed type, and in general comprises a feed tube 10 having a reciprocable plunger 11 therein, and a hopper 12 arranged to supply fuel to the feed tube. The feed tube may be of any appropriate shape, but, as shown in this instance, is of circular cross-section and is made of a suitable length to extend through an opening provided in the hinged door 13 of the furnace 14, so as to position the open inner end of the tube above the fire-pot 15 of the furnace.

According to my invention, the feed tube 10 with the hopper 12 attached thereto is supported in a bracket 16 which may be secured to, but is preferably formed integral with, the door 13. As shown in Figs. 4 and 6 of the drawings, this bracket is of hollow or inverted saddle form having a substantially semi-cylindrical recess therein, and is arranged to extend laterally adjacent the opening provided in the door for the feed tube. The recess of the bracket corresponds generally with the external contour of the feed tube, so that when the latter is inserted through the opening of the door 13, it will be supported in the recess of the bracket by the engagement of its outer surface with the bearing portions 17 of the bracket and with the annular edge 17' of the opening in the door. The bracket thus forms a saddle-like support or mount in which the feed tube 10 is both rotatable about its axis and slidable longitudinally of its axis, for purposes presently to be explained.

The sliding movement provided for the feed tube by the bracket 16 permits the tube to be retracted relative to the opening of the door 13 whenever it may be desirable to swing the latter to its open position, such as when the fuel bed needs to be stirred or lighted, or when trash is to be burned in the furnace. The retraction of the feed tube in this manner allows the door to be swung to its open position without interference between the inner end of the feed tube and the wall of the furnace door fitting or mount 18. To reduce to a minimum the amount of sliding

movement of the feed tube which may be required, I prefer to locate the bracket 16 so that the axis of the feed tube will be as close as practical to the hinge connection 19a upon which 5 the door swings. It will be understood, of course, that the length of the feed tube and the amount of sliding movement necessary will vary in accordance with different types of furnaces, and in those instances where the length of the feed tube 10 is such that no interference occurs between its inner end and the door fitting, no retracting movement whatever is necessary. In the case of a hot air furnace, such as that illustrated in the drawings, retracting movement of the feed tube 15 is usually necessary because the door fitting 18 is made of considerable length so as to extend through the air heating passage, and the feed tube must be made correspondingly long so that its open inner end will extend above the fire-pot. 20 The hopper 12, which supplies the fuel to the feed tube 10, may be of any suitable size or shape, but when the stoker is intended for use with domestic heating plants, this hopper should be sufficiently large to hold several hours' supply of 25 fuel. The rotational movement provided for the feed tube in the supporting bracket 16 facilitates the charging of this hopper with fuel, by permitting the hopper to be swung about the axis of the feed tube as a center, from the upright feeding 30 position shown in full lines in Figs. 1 and 2 to the inclined dotted position shown in Fig. 2. When the hopper has been swung to its inclined position, it can be readily filled with the desired amount of fuel without interference from over- 35 head structures, such as the flooring which may extend above the basement in which the furnace is located. After the hopper has been charged with fuel, it is swung to its upright position, from which the fuel descends by gravity into the 40 feed tube 10. As shown in the drawings, the walls of the hopper are inclined and so arranged that the fuel will flow freely into the feed tube without sticking or clogging. At the top of the hopper, the walls are preferably inclined inwardly 45 to form the lip 18' which prevents fuel from falling out while the hopper is in the inclined charging position.

To limit the rotational movement of the feed tube 10 about its axis, and thereby limit the extent of swinging movement of the hopper, I provide a longitudinally extending tongue or rib 19 on the outer surface of the feed tube which cooperates with the shoulders or abutments 20 provided on the bracket 16 at points adjacent the bearing portions 17 thereof. Violent jarring of the stoker, incident to engagement of the tongue 19 with one of the shoulders 20, may be prevented by providing resilient bumpers in the form of rubber blocks 21, which may be secured to said shoulders by suitable means, such as the dovetail connection illustrated in Fig. 7. It will be seen from the arrangement described that the hopper may be swung to either side of the vertical plane passing through the axis of the feed tube, and when 65 the tongue 19 engages one of the bumpers 21, the hopper will be retained in a convenient position for charging with fuel.

For locking and retaining the hopper in its upright or fuel feeding position, I provide locking 70 means in the form of a pair of latches 22, which are pivotally mounted upon the bracket 16. These latches extend laterally outwardly in opposite directions from the center line of the bracket, so as to be readily accessible when the 75 feed tube is to be released and the hopper swung

to its charging position. The inner end portion 23 of each latch is preferably curved upwardly so as to extend through the opening 24, formed in the bottom wall of the bracket 16, for engagement with the tongue 19. The pivotal 5 mountings for the latches are preferably so located that the distribution of the weight of these members will cause the inner ends 23 to normally project upwardly through the opening 24 and into the path of movement of the tongue 19. 10 When the hopper is to be moved to the charging position, the appropriate latch is swung about its pivot to retract the end 23 from the opening 24, and allow swinging movement of the tongue 19. 15 When the hopper has been charged and is moved to its upright position, the tongue depresses and rides over one of the latches and is received and held in the space between the ends 23, thus locking the feed tube against further rotation and holding the hopper in the fuel feeding position. 20

To prevent rotation of the hopper while the feed tube is in its retracted position to permit the door 13 to be swung to the open position, I provide a slot 26 in the inner surface of the bracket recess. This slot is located in axial alignment with the locked position of the tongue 19, and upon retracting movement of the feed tube 10, the tongue enters the slot and effectively holds the feed tube against rotation while in its retracted position, thereby avoiding any possibility 30 of the hopper being tilted and the charge of fuel spilled upon the floor.

For actuating the plunger 11 to push the fuel along within the feed tube, I provide a flexible diaphragm 27 and a fluid pressure chamber 28, 35 which are arranged at the outer end of the feed tube 10, the flange 29 of the casing of said chamber serving as a means for clamping the edge portion of the diaphragm in fluid-tight engagement with the end flange 30 of the feed tube. 40 The diaphragm 27 is operatively connected with the plunger 11 by means of the plunger rod 31. One end of this rod is secured to the plunger centrally thereof, while the other end of the rod is secured to the diaphragm centrally thereof by 45 means of a bearing plate 32 and a washer 33 which are clamped against opposite sides of the diaphragm. It will be seen that the diaphragm 27 forms a movable rear wall for the chamber 28, thus constituting the movable power element of 50 an expansible chamber motor which is adapted to move the plunger 11 toward the door 13, or in other words, in a fuel feeding direction. The plunger is shown in Fig. 4 in its retracted position, to which it is moved by a coil spring 34. This spring is arranged to surround the plunger rod 31 with one of its ends in engagement with an abutment member 35 extending transversely of the feed tube, and with its other end in engagement with a spring centering washer 36, which is secured to the plunger rod adjacent the diaphragm 27. 55

Any available motive fluid of appropriate nature may be supplied to the chamber 28 for actuating the diaphragm 27, but I prefer to use water 65 pressure as the actuating medium. For controlling the supply of motive fluid to the chamber 28, I provide supply and discharge valves 37 and 38 which cooperate, respectively, with supply and discharge ports 39 and 40 formed in the cover 41 of the chamber. The valves 37 and 38 are appropriately shaped for efficient cooperation with the valve seats surrounding the ports, and are carried by an arm 42 which is pivoted upon the cover extension member or bracket 43. A 75

second arm 44 is pivoted to the bracket 43, and is flexibly connected to the arm 42 by means of the springs 45. The arms 42 and 44, together with the springs 45, constitute a snap action mechanism for actuating the valves 37 and 38. Movement of the arm 44 in a direction away from the cover 41 may be limited by providing a suitable stop in the form of a headed screw 46 which is carried by the cover and extends through an opening provided in the arm. A lost motion operating connection is provided between the valve actuating mechanism and the diaphragm 27, by providing the plunger rod 31 with an extension 47 which is coupled to the arm 44 by extending loosely through a slot 48 in the latter. Any suitable means may be used to establish this loose connection, but I prefer to employ the extension member 47 having the button-like head 49 and the shoulder 50, arranged in spaced relation for engagement with opposite sides of the arm 44. The assembly of the snap action mechanism with the member 47 may be facilitated by providing the arm 44 with an opening 51, which communicates with the slot 48, and which is large enough 25 to permit the head 49 to pass therethrough.

In the operation of the device, motive fluid, such as water from the domestic supply line, is admitted to the chamber 28 through the port 39, while the discharge valve 38 is held closed. This 30 fluid pressure, acting upon the diaphragm 27, moves the latter against the force of the spring 34, thereby causing the plunger 11 to push a quantity of fuel along the feed tube 10 toward the fire-pot. Near the end of the travel of the 35 plunger in the fuel-feeding direction, the head 49 causes the arm 44 of the valve mechanism to be swung upon the bracket 43. When this arm has moved a sufficient distance to cause the spring 45 to pass over the dead point which, in 40 this instance, is the pivot pin of the bracket 43, a snap action takes place, causing the supply valve 37 to be closed and the discharge valve 38 to be moved to open position. The opening of the discharge valve 38 relieves the fluid pressure in 45 the chamber 28 and allows the spring 34 to retract the plunger 11 within the feed tube. To regulate the rate of operation of the stoker, I provide a valve 52 for controlling the rate of flow of the 50 motive fluid. This control valve may be associated with either the supply or discharge ports, but I prefer to locate the same in the discharge line, as shown in Fig. 5, because the comparatively low fluid pressure in this line permits the valve to exercise a more sensitive control function. 55 This control valve is preferably a valve of the needle type which may be adjusted to vary the size of the discharge opening and thereby regulate the rate at which fluid can be forced from the chamber 28. The setting of this valve thus determines the rate at which the plunger 11 will 60 be retracted by the spring 34. As shown in Fig. 9, the valve 52 may be of a standard type having a body 53 and a needle 54 arranged to cooperate with a seat 55 formed on the body. To provide 65 for a constant minimum rate of operation of the stoker, which will be only sufficient to maintain a low fire, the taper of the needle is provided with a flat face 56, which allows a predetermined flow of fluid when the needle valve is seated, and 70 which also performs the function of cutting scale which may form on the valve seat.

Near the end of the retracting movement of the plunger, the arm 44 of the valve actuating mechanism is swung toward the cover 41 by the shoulder 50 of the extension member 47. When

the plunger has been fully retracted, a snap action of the arms 42 and 44 takes place, moving them into the position illustrated in Fig. 5, and thereby closing the discharge valve 40 and opening the inlet valve 39. Thereupon, fluid pressure is again supplied to the chamber 28 to move the plunger 11 in a fuel-feeding direction. It will be understood that, in the operation of the device, the movement of the plunger in the fuel-feeding direction takes place comparatively rapidly, while the retracting movement of the plunger is retarded in accordance with the rate of discharge of the fluid from the chamber 28, which is in turn regulated by the valve 52. The amount of travel of the plunger 11, which is necessary for the shifting of the valves 37 and 38, is very small, and hence the comparatively rapid feeding movement of the plunger through its short stroke, causes a small quantity of fuel to be jarred from the open inner end of the tube 10. By properly setting the valve 52, the stoker may be made to operate at any desired rate of speed with small quantities of fuel being fed to the fire-pot at regular intervals. The plunger stroke and the diameter of the feed tube may be varied, but when the stoker is to be used in conjunction with the ordinary domestic heating equipment, a feed tube about five inches in diameter and a plunger stroke of one inch prove to be very satisfactory.

In addition to the valve 52 located in the fluid discharge passage, I provide another valve 57 in the fluid supply line, which valve is similar to the valve 52 except that it is capable of being tightly closed so that the supply of fluid to the motor can be completely shut off when operation of the stoker is not desired.

For automatically regulating the operation of the stoker in accordance with the temperature requirements of the room or space to be heated, I provide a thermostat 60, which may be located in one of the heat passages of the furnace, but which is preferably located at a remote point, such as in the room being heated. This thermostat comprises a chamber 61 adapted to contain a body of suitable liquid which expands when subjected to heat, such as sulphur dioxide. The chamber 61 may be housed within a suitable heat conducting casing 62, and is arranged to surround a flexible chamber 63 containing a volume of oil or other suitable fluid. The chamber 63 communicates with the interior of an expansible chamber 64 through a connecting tube 65. The chamber 64 may be mounted upon a suitable base or support 66 located near the stoker, and is arranged to cause swinging movement of the lever 67 about its pivot 68. An adjustable weight 69 is provided on the lever 67, and normally tends to compress the chamber 64 so as to force the oil therein through the tube 65 and back into the chamber 63. A chain 70 attached to the opposite end of the lever 67 is connected with an arm 71 extending laterally from the stem of the valve 52, and is also connected to the draft door 72 of the furnace 14.

As the temperature of the space, in which the thermostat 60 is located, begins to rise, the heating of the fluid within the chamber 61 causes the same to expand. The expansion of this fluid exerts a pressure upon the chamber 63 and forces oil through the tube 65 into the chamber 64, causing the weight 69 to be lifted and the lever 67 to be swung about its pivot 68. The lifting of the weight 69 allows the draft door 72 to pull the chain 70 downwardly, thereby causing the lever 75

71 to rotate the valve stem in a direction to reduce the size of the discharge valve opening. This reduction in the size of the valve opening restricts the discharge opening for the chamber 5 28, thereby decreasing the rate at which the plunger can be retracted by the spring 34, and consequently slowing up the operation of the stoker. The movement of the draft door 72 toward its closed position reduces the supply of air 10 to the furnace and correspondingly checks the rate of combustion. When the room temperature falls, the fluid within the chamber 61 contracts and relieves the pressure upon the inner chamber 63. Thereupon the weight 69 is lowered by the transfer of oil from the chamber 64 into the chamber 63. The lowering of the weight 69 causes the chain 70 to be moved upwardly, thus opening the draft door 72, and also rotating the needle of the discharge valve 52 to 15 increase the size of the discharge opening and thus increase the speed of operation of the stoker.

Adjustment for the automatic control of the stoker may be made either by shifting the weight 69 along the lever 67, which may be provided with 25 suitable graduations, or by loosening the nut 73 provided on the stem of the valve 52 and altering the angular relation of the valve stem with respect to the lever 71. To facilitate this latter 30 adjustment, I provide the disk or dial 74, which may have suitable graduations thereon, and which is secured to the stem of the valve 52. The end of the lever 71, opposite that to which the chain 70 is attached, is provided with an opening 35 for the valve stem, and is adapted to be clamped against the disk 74 by the wing nut 73. After unscrewing this wing nut, the valve stem may be rotated by means of the disk without altering the position of the lever 71. When the proper setting of the valve has been attained the wing nut 40 is tightened thereby clamping the lever and disk together.

To assist the bracket 16 in supporting the stoker mechanism, and the weight of the fuel charge contained in the hopper 12, I provide a 45 depending leg 75 which is secured to the bracket 16 at a point remote from the hinge connection 19a. This leg cooperates with the hinge connection of the door in supporting the weight of the stoker mechanism and the fuel charge, and 50 to facilitate swinging movement of the door, may be provided with suitable roller means, preferably in the form of the caster 16. To provide for a slight variation in the length of the leg 75, such as might be desirable should the caster 16 pass over an uneven portion of the floor, I provide a 55 yielding connection between the lower end of the leg and the caster. This connection may consist of a pintle 77 on the caster, which slidably telescopes into the lower end of the leg 75, and engages a compression spring 78 housed within the leg. The spring 78 provides a shock absorbing connection between the caster and the leg, and also permits slight vertical movement of the 60 caster when the latter passes over obstacles or uneven places on the floor.

To reduce the amount of friction between the plunger 11 and the feed tube 10, it may be desirable to provide the latter with an annular 70 bearing surface 80, which is located immediately adjacent the discharge opening of the hopper 12, and which extends but a short distance axially of the tube. This bearing surface is narrow 75 as compared with the axial length of the plunger

and tends to reduce the amount of friction therebetween.

Since the feed tube 10 and the casing of the fluid chamber 28 secured to the outer end thereof are both movable with the door 13, as the 5 latter swings to open and closed position, it is necessary to provide flexible motive fluid connections, and for this purpose I prefer to employ flexible rubber hose, or the like, for the fluid supply and discharge conduits 81 and 82. 10

It will now be readily seen that I have provided a simple and compact form of mechanical stoker which is very economical in operation. It will also be seen that the mounting means which I have provided for the stoker mechanism permits 15 the same to be quickly and easily applied to previously erected furnaces by simply substituting for the original furnace door, the door 13 having the stoker mechanism mounted thereon. In the apparatus which I have provided, the provision 20 for rotation of the feed tube permits the hopper to be swung to a convenient fuel charging position, and the sliding movement provided for the feed tube permits the same to be retracted whenever the operator desires to open the door 13 25 which may be for purposes of working or starting the fire in the fire-pot of the furnace 14. It will also be seen that I have provided a simple form of actuating means for the stoker adapted to use a readily available supply of motive fluid. 30 Operation and care of the stoker is simplified by the provision of the automatic control means for regulating the speed of operation of the stoker and the draft door in response to the temperature conditions existing in the room or space to 35 be heated. It will likewise be seen that since a fluid is employed for operating the stoker plunger rather than an electric motor having a rigid mechanical connection, the chance of damage to the apparatus in the event of clogging 40 of the feed tube, is entirely eliminated. With the mechanical stoking means which I have provided a cheap grade of fuel can be used to advantage for domestic heating purposes, since the feeding of the fuel to the fire takes place in 45 very small amounts, which are not sufficient to smother the fire as would be the case if several hours' supply of fuel were shoveled into the firepot.

While I have illustrated and described the 50 device of my invention in a detailed manner, it should be understood, however, that I do not intend to limit myself to the precise details of construction and arrangements of parts illustrated and described, but regard my invention as including such changes and modifications as do not involve a departure from the spirit of the invention and the scope of the appended claims. 55

Having thus described my invention, I claim:

1. In a stoker mechanism, the combination of 60 a fuel-feeding conduit, means for advancing the fuel within said conduit, and hydraulically actuated means for driving the fuel advancing means, said hydraulically actuated means comprising a chamber having a flexible wall driving- 65 ly associated with the fuel advancing means, fluid supply and exhaust conduits communicating with said chamber, valve means for automatically controlling said conduits to thereby control the movement of said fuel advancing 70 means, and other control means for regulating the flow of fluid through the exhaust conduit to thereby regulate the speed of operation of the fuel advancing means.
2. In a stoker mechanism, the combination of 75

a fuel-feeding conduit, means for advancing the fuel along said conduit, and means for actuating the fuel advancing means comprising a chamber having a flexible wall drivingly associated with 5 said fuel advancing means, means for supplying fluid pressure to said chamber, means for retracting the fuel advancing means, and means for regulating the rate of discharge of fluid from said chamber to thereby control speed of operation 10 of the fuel advancing means.

3. In a mechanical stoker, the combination of a fuel-feeding tube, a plunger in said tube, and means for actuating said plunger comprising a fluid chamber associated with said tube, a flexible 15 diaphragm forming a wall of said chamber and having operative connection with said plunger, valve means for controlling the passage of motive fluid to and from said chamber, snap action mechanism located in said chamber and 20 adapted to actuate said valve means, and control means exterior of said chamber for regulating the rate of passage of motive fluid through said chamber.

4. In a mechanical stoker, the combination of 25 a fuel-feeding conduit, means for advancing fuel along said conduit, and means for actuating the fuel advancing means comprising a fluid chamber associated with said conduit, a flexible diaphragm forming a wall of said chamber and having 30 operative connection with said fuel advancing means, valve mechanism for automatically controlling the passage of fluid into and out of said chamber, control means for the discharge passage leading from said chamber, and temperature responsive means for actuating said control 35

means to thereby regulate the speed of operation of said fuel advancing means.

5. In a mechanical stoker, the combination of a fuel-feeding tube, a plunger in said tube, means for actuating said plunger comprising 5 a fluid chamber associated with said tube, a flexible diaphragm forming a wall of said chamber and operatively connected with said plunger valve mechanism adapted to be actuated by said diaphragm for automatically controlling 10 the passage of fluid into and out of said chamber, control means for the discharge passage leading from said chamber, temperature responsive means for actuating said control means to thereby regulate the speed of operation 15 of said plunger, and means associated with said control means and providing a passage for maintaining a minimum rate of fluid flow through said chamber.

6. In a stoker mechanism, the combination 20 of a fuel-feeding conduit, means for advancing the fuel within said conduit, and hydraulically actuated means for driving the fuel-advancing means, said hydraulically actuated means comprising a chamber having a flexible wall drivingly 25 associated with the fuel-advancing means, fluid supply and exhaust conduits communicating with said chamber, valve means for automatically controlling said conduits to thereby control the movement of said fuel-advancing 30 means, and other control means for regulating the flow of fluid through one of said conduits to thereby regulate the speed of operation of the fuel-advancing means.

ALBERT C. SCHICKLER. 35
